ALLEN WEBSTER, OF FARMINGTON, ASSIGNOR TO HIMSELF AND
N. C. HUBBELL, OF NEW HAVEN, CONNECTICUT.

Letters Patent No. 89,528, dated April 27, 1869.

IMPROVED MACHINE FOR MAKING SCREWS.

The Schedule referred to in these Letters Patent and making part of the same.

To all whom it may concern:

Be it known that I, ALLEN WEBSTER, of Farmington, in the county of Hartford, and State of Connecticut, have invented a new Improvement in Machine for Making Screws; and I do hereby declare the following, when taken in connection with the accompanying drawings, and the letters of reference marked thereon, to be a full, clear, and exact description of the same, and which said drawings constitute part of this specification, and represent in—

Figure 1, a top view;

Figure 2, a side view; and in

Figures 3, 4, 5, 6, and 7, detached views.

This invention relates to an improvement in machines for making small screws, such as are used for mechanical purposes, and especially that class of screws known as clock-screws, but alike applicable to the making of clock-pillars.

To enable others to construct and use my improvement, I will fully describe the same as illustrated in the accompanying drawings.

A is the bed-plate upon which is arranged a carriage B, moving longitudinally in guides B', the said carriage supporting in bearings C, a carrier-wheel C', and is moved back and forth by means of a lever D, and to the shaft of the wheel C', a gear e is fixed, which, as the carriage is moved forward, passes over a rack D', and causes a partial revolution of the wheel C', but as the carriage returns the gear e passes over the rack without turning the wheel C', that is, the gear e turns on the shaft, the shaft being held by a pawl and ratchet d.

In bearings E E' is arranged a hollow mandrel E', through which the wire from which the screw is to be made is passed, as seen in fig. 3, and in the wheel C', a milling-tool a is arranged so that as the wheel C' is moved up by the carriage B, the milling-tool a will cut away the end of the wire, the wire being rapidly revolved by the mandrel E' until the required length for the body of the screw is cut, as seen in fig. 3, then a cutter f is advanced and cuts into the wire at a proper distance from the shoulder to form the head and so as to nearly separate the blank from the wire as seen in fig. 1.

The carriage during this operation is withdrawn and again advanced, presenting a die h, which cuts the thread upon the revolving wire, and the connection between the blank and wire is sufficient to hold the blank for this operation, but so soon as the die h strikes the shoulder of the head it will break the blank from the wire. The next movement of the carriage turns the wheel C', and presents another cutter to form the second blank, while the first is turned down to the position at i, fig. 4; then as the wheel C' is again drawn back, the screw passes over a cutter and nicking-wheel G beneath the machine, which nicks the head and at the same time dresses its surface, the wheel being formed as seen in fig. 7, which completes the screw.

At the next movement of the carrier the finished

screw is turned up to the position seen at n, fig. 4, and in its movement up to this point it passes on to a screw-driver m supported on the carriage B in bearings b; when the carriage is drawn back a revolving mandrel L connects with the spindle of the screw-driver m, as seen in fig. 5 enlarged, which turns the screw from its die when the screw drops from the machine complete.

After having thus turned the screw from its die it is necessary that the screw-driver should return again at the same point to receive the screw. For this purpose I arrange upon the screw-driver spindle a toothed wheel E, seen in figs. 5 and 6, and below that a larger toothed wheel R, and on the spindle or wheel P I form a notch or projection s, and hang a pawl S, and on the wheel R I form a cam t, so that when the said cam strikes the pawl S it will raise the said pawl and cause it to strike into or against the projection or notch s on the wheel P, the number of teeth of the said wheels being proportioned so that any number of given revolutions of the small wheels may be made before the cam on the one and notch or projection on the other would act in conjunction and thus arrest the movement.

I arrange upon the shaft of the wheel R a spring or weight which is wound up by the revolution of the screw-driver withdrawing the screw; therefore when the screw has been withdrawn and the screw-driver spindle released from its connection with the mandrel L, the spring or weight acting upon the wheel R will cause the screw-driver to return until the notch and cam are again in conjunction as in fig. 6, which is the condition of the rest to receive the screws.

Instead of the screws it will be readily seen that pillars for clock-movements may be formed in the same manner by passing the wire from which the pillars are to be made through the mandrel E'.

Having thus fully described my invention,

What I claim as new and useful, and desire to secure by Letters Patent, is—

1. The reciprocating and rotating carrier-wheel C', provided with the milling-tool a, and threading-die h, combined with the mandrel E', for revolving the wire, and the cutter f, operating as and for the purpose specified.

2. In combination with the subject-matter of the first clause of claim, the nicking and milling-tool G, operating as and for the purpose set forth.

3. In combination with the subject-matter of the first and second clauses of claim, the screw-driver m arranged so as to operate as and for the purpose specified.

4. The combination of the wheels P and R, stops L and s, with the pawl S, so as to operate as and for the purpose set forth.

ALLEN WEBSTER.
